UNITED STATES PATENT OFFICE.

CHARLES H. PARSHALL, OF DETROIT, MICHIGAN, ASSIGNOR OF ONE-HALF
TO EDWARD GRACE, OF SAME PLACE.

LUBRICATOR.

SPECIFICATION forming part of Letters Patent No. 376,676, dated January 17, 1888.

Application filed October 23, 1886. Renewed December 15, 1887. Serial No. 258,016. (No model.)

To all whom it may concern:

Be it known that I, CHARLES H. PARSHALL, of Detroit, county of Wayne, State of Michigan, have invented a new and useful Improvement 5 in Lubricators; and I declare the following to be a full, clear, and exact description of the same, such as will enable others skilled in the art to which it pertains to make and use it, reference being had to the accompanying drawings, which form a part of this specification.

My invention consists of the combinations of devices and appliances hereinafter specified, and more particularly pointed out in the 15 claims.

In the drawings, Figure 1 represents my device as applied to a lubricator of the ordinary make and in the nature of an attachment to any lubricator. Fig. 2 represents the device 20 as forming a part of the construction of a lubricator, and represents it in connection with that kind of a lubricator known as a "double-sight-feed lubricator," designed to feed through two independent channels and 25 convey the oil to two distinct destinations—as, for instance, to the two cylinders of a locomotive. Fig. 3 is a vertical section of the oil-exit conduit and its immediate connections on line XX of Fig. 2. Fig. 4 is a plan view of the 30 device shown in Fig. 2; Fig. 5, a view illustrating the slip-joint connection of the inlet steam-pipe. Fig. 6 is an enlarged section on the line xx of Fig. 2, illustrating the construction of the valve F and its location on the oil-exit conduit. Fig. 7 is an enlarged sectional 35 view of the valve G' and its related parts. Fig. 8 is a sectional view of the filler and its governing-valve.

It is the purpose of my invention to provide 40 means whereby, without the aid of any equalizing steam-conduit, any lubricator may be converted into a locomotive-cup or be adapted to operate in any situation where the conditions are similar to those upon a locomotive— 45 i. e., where the steam-passage for supplying the water of condensation is always in communication with the boiler-pressure, while the oil-exit leads to the dry-pipe, steam-chest, cylinder, or other part where the pressure fluctuates 50 or where the pressure may be entirely cut off.

It is well known that in locomotives where

steam is taken from the steam-dome or other source of boiler-pressure to the condenser of the lubricator, and where the oil-exit leads to the dry-pipe, cylinder, or steam-chest, should 55 the locomotive be on the downgrade or just arriving at a station, or in other similar situation where the steam is cut off from the dry-pipe by the throttle-valve, the pressure, which up to that time was substantially the same in 60 the condenser and at the oil-exit, is now relieved at the oil-exit, so that the interior of the lubricator is no longer in equilibrium as to steam-pressure. The tendency at this time is for the steam-pressure to instantly force out 65 from the lubricator a considerable quantity of oil, thus not only wasting the oil, but driving 70 the condense-water with it from the visible feed-tubes, and causing the said tubes to become filled more or less with oil, and so destroy for a time its function as a visible-feed lubricator. Heretofore this has been remedied by the employment of a steam-conduit connecting the steam-inlet with the oil-exit passages either within or outside the body of the 75 lubricator. I propose to accomplish the same result by substantially different means, which I will now proceed to describe.

A is the oil-reservoir of an ordinary lubricator; B, its condenser; C, the steam-inlet pipe 80 for supplying water of condensation; D, the visible-feed chamber or water-tube; E, the oil exit conduit.

Condense-water is led from the condenser down into the oil-chamber through a conduit, 85 C', in the usual way. This conduit leads the condense-water nearly to the bottom of the oil-reservoir, where its supply may be regulated by a valve, C', at the base of the lubricator. The oil floated upward by the condense-water 90 passes directly into the base of the sight-feed glass, as shown in Fig. 2 of the drawings.

The petcock G' is shown in the drawings as located at the base of the indicator-tube. It may be either located at this point or in the 95 base of the lubricator, for in either case it would serve as an outlet for steam and water blown through the sight-feed glass for the purpose of cleansing the latter. At this point my invention begins.

F is a valve located on the oil-exit conduit 100 between the discharge end of the visible-feed

tube and the parts to be lubricated. It may be located at any point on this line, but I prefer to locate it adjacent to the lubricator, as shown in the drawings. This valve F is provided with a valve-stem, F', and its top terminates in a disk, F², which fits closely and moves up and down as a piston within the screw-cap F³. The upper edge of this piston or disk seats against a surface, f, of soft metal, preferably soft solder, thus making a steam-tight joint. The screw-cap is perforated at f², so that the space above the piston and disk shall always be in equilibrium with the external air.

15 f³ is a spring located above the disk, and its tension may be regulated by a thumb-screw, f⁴. The operation of the device will now be explained. It will be observed that only the extreme lower point of the valve F is exposed to the pressure from that side adjacent to the lubricator, and the tension of the spring may be so regulated that this pressure can only raise the valve to a very slight degree. On the other hand, it will be observed that the under side of the disk or piston F² is open to back-pressure from the steam-pipe or dry-pipe acting back through the oil-exit conduit. Now, if the device be placed upon a locomotive, with the top of the lubricator connected in the usual way with the steam-space of the boiler and the oil-exit connected with the dry-pipe, steam-chest, or cylinder, it is apparent that when the engine is running, the back-pressure will constantly hold the valve F wide open or entirely off from its seat and up against the soft-metal seat above. There will be an equilibrium within the lubricator, so that it will feed in the usual way simply by reason of the preponderance of the hydrostatic column of condense-water. When, however, the engine is going on a downgrade or just arriving at a station, and when, for this reason, pressure is relieved from the dry-pipe, steam-chest, or cylinder, the spring f³ would at once force the valve F downward. At this moment there will be no reacting pressure, and the condition of equilibrium within the lubricator is destroyed, and there would be the pressure of the boiler to force oil from the lubricator.

35 The valve F has, however, neutralized this tendency, and oil can be forced out only with the speed that it can pass through beneath the valve.

It is an easy matter for an engineer, at any time steam is not on the engine, to regulate the spring f³ so that the rate of the flow of the oil past the valve shall be just the same as the rate of flow by hydrostatic pressure alone when the engine is running. The construction therefore is such that, whether steam is on the engine or off, the rate of flow of the oil will always be uniform, and this is accomplished without the employment of an equalizing steam-pipe.

65 The preceding description relates more particularly to the device when made in the nature of an attachment to any of the usual forms

of sight-feed lubricators; but the device is equally applicable when made to form a part of the lubricator itself. Thus, as shown in Fig. 2, it may be interposed between the oil-reservoir and the condenser, and in this connection the same letters represent parts corresponding to those which have been already described in connection with Fig. 1.

75 There is another advantage derived from the construction shown in Fig. 2, whether the same be adapted for a single or a double lubricator. The connection G is made in the form of a conduit communicating with the passage-way between the condenser and the oil-reservoir and governed by a valve, G'. Now, should the glass water-tubes become fouled with oil or sediment, the petcock G² at the bottom of the glass indicator-tube or reservoir may be opened. Then by opening the valve G' condense-water or live steam may be forced through the water tube or tubes, thus thoroughly cleansing them. So, also, the tubes may be swabbed out by removing the plugs H above their upper ends.

80 J is a filler governed by a valve, J'. This is designed for use only when, by reason of the glass tubes breaking or other derangement of the lubricator, it becomes necessary to feed oil 85 from the can. I would have it understood that it may or may not form a part of my improved attachment. I prefer, however, to so employ it, and my claim for the attachment is presumed to cover the attachment whether 90 with or without this independent filler.

95 I find it very desirable to unite the inlet steam-pipe C with the condenser B by means of a slip-joint connection, as shown at c. C' represents a valve located in said steam-pipe, 100 the pipe C being also united therewith by a slip-joint connection, as shown at c'. Heretofore this union of the steam-pipe with the condenser and the valve has been made by a rigid connection or by a ball-joint or a screw 105 connection. Such a connection facilitates the location of the cup in place and permits a readier and freer connection. Should any mistake occur in drilling the hole in the steam-pipe, this construction allows due compensation 110 therefor.

115 What I claim is—

1. The combination, with a lubricator, of a valve, F, located in the oil-exit passage between the visible-feed tube and the parts to be lubricated, said valve constructed to present a large surface to the back-pressure through the oil-exit conduit and to present a small surface only to the direct pressure from the lubricator, and an adjustable spring for pressing 125 the valve upon its seat, substantially as and for the purposes described.

2. The combination, with a lubricator, of a valve, F, located in the oil-conduit between the visible-feed tube and the point to be lubricated, said valve open at its top to the external air, provided with a disk or piston, F², and an adjustable spring for forcing the valve toward its seat, the construction being such that

the large surface beneath the disk is presented to the back-pressure through the oil-exit pipe, while a small surface only at the end of the valve is presented to the direct pressure from the lubricator, substantially as and for the purpose described.

3. The valve F, provided with a disk or piston, F², the latter constructed at its upper edge to form a steam-tight joint, whereby pressure is exerted back through the oil-exit passage, in combination with a spring located above said valve, substantially as and for the purposes described.

4. The combination, in a lubricator, of the valve F in its oil-exit passage, constructed as described, and a steam-passage, G, leading

from the condense-water passage to the top of the sight-feed glass, said steam-passage governed by a valve, whereby the visible-feed tubes can be cleansed, substantially as and for the purposes described.

5. As an article of manufacture, an attachment to an ordinary sight-feed lubricator, said attachment consisting of the valve F, provided with stem F', disk or piston F², and adjustable spring f³, substantially as described.

In testimony whereof I sign this specification in the presence of two witnesses.

CHARLES H. PARSHALL.
